UNITED STATES PATENT OFFICE

JEROME BROWN, OF MILWAUKEE, WISCONSIN, ASSIGNOR TO BRIGGS & STRATTON CORPORATION, OF MILWAUKEE, WISCONSIN, A CORPORATION OF DELAWARE

SPRING COVER

Application filed January 16, 1931. Serial No. 509,068.

This invention relates to certain new and useful improvements in metal spring covers for vehicle springs.

Where springs are provided with such covers it is customary to remove or eliminate the usual spring clips provided to prevent the leaves of the spring from "fanning" and spreading and the cover itself is relied upon to retain the spring in shape. However, it has been found that where the springs are extremely flexible and thus subject to excessive flexure or "whipping" especially when the brakes of the vehicle on which they are mounted, are suddenly applied, the seams of the covers are often opened.

To overcome this objection, ordinary spring clips have been secured over the cover, but this additional requirement is also objectionable and this invention, therefore, has as one of its objects to provide means whereby the necessity for separate spring clips is entirely eliminated and in which means are incorporated within the cover per se to prevent opening of the seams thereof upon excessive movement or "whipping" of the spring to which the same is applied.

A more specific object of this invention resides in the provision of a metal spring cover which has portions thereof folded upon itself to provide a band or bands of increased thickness completely surrounding the spring to more effectively guard against the opening of the cover seams upon excessive spring movement.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the principles thereof, and in which:

Figure 1 is a perspective view of a spring equipped with spring covers constructed in accordance with this invention;

Figure 2 is a top plan view of a spring cover prior to its engagement on a spring and with parts thereof broken away and in section to illustrate structural details; 55

Figure 3 is an enlarged sectional view taken longitudinally through the medial portion of the cover on the plane of the line 3-3 of Figure 2; and 60

Figure 4 is a cross sectional view taken through Figure 1 on the plane of the line 4-4. 65

Referring more particularly to the accompanying drawing, in which like numerals designate like parts throughout the several views, the numeral 5 represents a conventional vehicle leaf spring on which covers 6 constructed in accordance with this invention are secured. Each cover 6 is stamped from a single blank of bendable metal and then folded transversely, as illustrated in Figure 2, after which it is secured about the spring in any suitable manner and locked thereon by a longitudinal seam 7 extending throughout the length of the cover and on the underside of the spring. 70

To accommodate the flexure of the spring, the blank of which the cover is formed is cut from opposite sides to divide the same into a plurality of sections 8 connected only at their medial portions, as at 9. The medial connecting portions 9 are folded so that the sections 8 overlap each other as clearly shown in Figure 3, and when the cover is secured over the spring the connecting portions 9 are disposed on the top of the spring and those portions of the blank outwardly of the connecting portions 9 form the sides and bottom of the cover. The portions 9 thus form substantially hinge connections between the adjacent sections to accommodate relative movement between the sections 85 90

incidental to the flexure of the spring without exposing any portion of the spring. 95
Under ordinary conditions, the interlocked seam 7 which connects the longitudinal marginal edges of the covers along the bot- 100

tom of the spring is sufficiently strong to prevent its being opened as the spring flexes, but where the spring is exceptionally light and flexible and is therefore apt to 5 "whip" suddenly as when the brakes of the vehicle, with which the spring is employed, are suddenly applied, it has been found that the seams were often opened.

To off-set this possibility and to obviate 10 the necessity for spring clips over the cover, the cover is provided with strengthening bands 10 which completely surround the spring and have their ends interlocked, as part of the seam 7. The bands 10 are formed 15 as an integral part of the cover by doubling the material of the endmost sections 8 upon itself as shown in Figure 2, there being two such bands or portions of increased thickness in the outermost section 8, one at 20 the extreme end thereof and one at a medial point, and a single band or portion of increased thickness in the next adjacent section 8. These bands or portions of increased thickness are sufficiently strong at their 25 point of connection, which forms part of the seam 7, to securely hold the leaves of the spring against "fanning" and spreading and precludes the possibility of opening of the seam upon excessive spring movement. 30 While the same forms no part of the invention it is understood that in assembling the cover upon the spring, the spring may be first wrapped with the usual lubricant retaining fabric or cover 11, thus insuring 35 proper lubrication of the spring as well as completely enclosing the same against moisture and dirt.

What I claim as my invention is:

1. A one-piece metallic spring cover 40 adapted to snugly fit the top, sides and bottom of a laminated spring and provided with a transverse fold in its top portion intermediate the ends to form a hinge to compensate for vertical flexure of the spring. 45 the side and bottom portions of said cover being cut transversely adjacent said hinge and overlapped upon each other, a seam securing the longitudinal edges of the cover together along the bottom of the spring, and a plurality of spaced bands entirely 50 encircling the spring to preclude opening of the seam upon excessive spring movement, said strengthening bands comprising several 55 thicknesses of metal formed by folding the cover blank transversely upon itself, and extending from one marginal edge of the cover to the other to have their ends interlocked as part of the seam.
2. A one-piece metallic spring cover 60 adapted to snugly fit the top, sides and bottom of a laminated spring, a strengthening band formed as an integral part of said cover and adapted to entirely encircle the 65 spring, and integral means securing the

longitudinal edges of the cover together including the ends of said band.

3. A one-piece metallic spring cover 70 adapted to snugly fit the top, sides and bottom of a laminated spring, a strengthening band formed as an integral part of said cover and adapted to entirely encircle the spring, and a seam securing the longitudinal edges of the cover together including the ends of said band.

In testimony whereof I have hereunto affixed my signature.

JEROME BROWN.
